CLAIM

The ornamental design for a grass carpet rake, as shown and described.

DESCRIPTION

FIG. 1 is a front, top and right-side perspective view of the grass carpet rake showing my new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof;

FIG. 7 is a bottom plan view thereof;

FIG. 8 is a back, bottom and left side perspective view thereof; and,

FIG. 9 is an enlarged perspective view of the encircled portion 9 of FIG. 1.

The dot-dash broken lines depict the boundaries of the FIG. 9 enlargement that forms no part of the claimed design.
